UNITED STATES PATENT OFFICE.

SOL EINSTEIN, OF CINCINNATI, AND HERMAN R. ISLER, OF NORWOOD, OHIO, AS
SIGNORS TO THE CINCINNATI MILLING MACHINE COMPANY, OF OAKLEY, CINCIN-
NATI, OHIO, A CORPORATION OF OHIO.

STEADY REST.

Application filed February 27, 1924. Serial No. 695,518.

To all whom it may concern:

Be it known that we, SOL EINSTEIN and HERMAN R. ISLER, each a citizen of the United States, and residing, respectively, at Cincinnati and Norwood, in the county of Hamilton and State of Ohio, have invented a new and Improved Steady Rest, of which the following specification is a full disclosure.

10 This invention relates to grinding machines of the type adapted to operate on cylindrical work such as rollers, shafts, etc., and it deals more particularly with means for holding the work rigid against deflection during the action of the grinding wheel while yet permitting free rotation thereof.

These machines, as usually constructed, comprise a rotating grinding wheel, means for supporting and rotating the work, and 20 means for effecting a relative translation between the work and the grinding wheel, whereby all portions of the work may be brought to the action of the grinding wheel. Means are also provided for producing a 25 relative movement between the work and the grinding wheel transverse to the axis of the work to cause the grinding wheel to gradually reduce the diameter of the work.

When grinding work of substantial length 30 the pressure of the grinding wheel thereon causes more or less deflection and vibration of the work with the result that it is slightly bowed and the precision is diminished.

This invention has for an object to provide 35 an improved form of steady-rest for preventing deflection and vibration of the work when presented to the action of the grinding wheel and to provide improved means for maintaining the steady-rest in contact with the work as it is gradually decreased in diameter.

In operation, the grinding wheel exerts 40 both an outward and downward strain on the work and to resist this strain certain steady-rests have heretofore been provided 45 having work-engaging surfaces located below and at one side of the axis of the work. These devices have in some instances included a steady-rest shoe in both vertical and 50 horizontal planes to keep its work-engaging surfaces in contact with the work and were provided with independent means for shifting said shoe in each of said planes. To effect a proper adjustment of the shoe to

55 maintain its work-engaging surfaces in contact with the work it has heretofore been necessary to simultaneously adjust both of the shifting means the same amount, and when so adjusted the resultant motion of the shoe was obliquely upward toward the 60 work.

Devices requiring this double adjustment have been unsatisfactory for the reason that their adjustment requires the use of both of the operators' hands, and furthermore that 65 it is practically impossible to adjust both of the shifting means synchronously, as is necessary to effect a proper movement of the steady-rest shoe.

This invention therefore has for an object 70 to provide a work-support for grinding machines in which the steady-rest is so mounted that by a single adjusting means the shoe may be moved both outwardly and upwardly to keep its work-engaging surfaces in contact 75 with the work, whereby a substantially uniform working condition may be easily and conveniently maintained during the entire grinding operation.

Other objects and advantages will be in 80 part indicated in the following description and in part rendered apparent therefrom in connection with the annexed drawings.

To enable others skilled in the art so 85 fully to apprehend the underlying features hereof that they may embody the same in the various ways contemplated by this invention, drawings depicting a preferred 90 typical construction have been annexed as a part of this disclosure and, in such drawings, like characters of reference denote corresponding parts throughout all the views, of which:—

Fig. 1 is a side elevation of a portion of a grinding machine equipped with a preferred embodiment of the present invention. Fig. 2 is a section substantially on the line 2—2 of Fig. 1. Fig. 3 is a right end elevation of a portion of the improved steady-rest showing it fitted with a work-holding shoe adapted to hold very small work, and Fig. 4 is a section on the line 4—4 of Fig. 2. 95 100 105

Referring more particularly to the drawings the invention is disclosed in its preferred form as embodied in a grinding machine comprising a table upon which are mounted various parts of the grinding machine including a standard 2. The work

to be ground may be rotatably held as upon non-rotating centers c and c' or in any other manner common to grinding machines. A grinding wheel W , adapted to operate on the work, is mounted and rotated in any suitable manner. Conventional means may also be employed for rotating the work and for effecting a relative movement between the work and the grinding wheel both lengthwise of the work and transverse thereto. As the mechanism for producing these movements form no part of the present invention illustration and description thereof is deemed unnecessary.

15 It has been found that the pressure of the grinding wheel against the work, especially when it is of substantial length and of relatively small diameter, causes the work to yield with the result that imperfect work 20 is produced. To remedy this defect this invention proposes a steady-rest adapted to bear against the work at the side opposite to that at which the grinding wheel is located. To this end there is adjustably secured upon 25 the standard 2 a saddle 3 formed at one end with an inverted V-shaped guideway 4 which embraces a guide 5 provided by the standard 2. The opposite end 6 of the saddle rests upon the inclined upper surface 2^a of the standard 2. A thumb-screw 7 threaded into the saddle bears upon a clamp-plate 8 which serves to lock the saddle in its adjusted positions on the standard. The saddle 3 is formed with an upwardly extending arm 9 30 to which is pivoted, at 10, a carriage 11 of substantially inverted U-shape in cross-section, thus providing depending side-walls 12 at opposite sides of the saddle.

Upon the carriage 11 is removably secured, as by means of dowel pins 13, work-supporting blocks or shoes 14 providing converging work-engaging surfaces 15 which are adapted to be brought into contact with the work prior to the beginning of a grinding operation, while the work is held between the centers c and c' . As will readily be understood the diameter of the work is gradually decreased during the grinding operation and therefore the surface of the work would be gradually withdrawn from contact with the work supporting block were the latter permanently fixed.

An important feature of this invention, now to be described, consists in providing a 55 single, simple and efficient means for gradually shifting the work-supporting block to compensate for the reduction in size of the work, whereby a substantially uniform working condition is maintained during the entire grinding operation and deflection of the work is positively prevented.

Upon the underside of the carriage 11 and between the walls 12 is formed a lug 16 providing a cam-surface 17 against which is 60 adapted to bear the rounded end 18 of a

screw 19, threaded through a boss 20 on the saddle 3. A knurled head 21 affords convenient means for manually rotating the screw 19 to cause it to be threaded through the boss 20. Thus it will be seen that as 70 the diameter of the work is reduced, which would normally separate the work from the surfaces 15, the screw 19 may be rotated which, by means of the end 18 of the screw contacting with the cam-surface 17, will cause 75 the carriage 11 and therewith the block 14 to be moved in an arcuate path outwardly and upwardly to the right as viewed in Fig. 2. By this single adjustment surfaces 15 will be 80 caused to follow-up and engage the gradually decreasing work and hold it rigid against the outward and downward pressure of the grinding wheel.

In quantity production it is desirable to 85 provide means for automatically calibrating the work or in other words to insure that each piece will be ground down to a predetermined size. To this end an adjustable stop is provided by means of which the rotation of the screw 19 (and thereby the upward and outward adjustment of the block 14) may be limited. This stop may conveniently consist of a split collar 27 adjustably secured, as by means of a clamp screw 28, upon the outwardly projecting end of the screw 19. This collar is formed with an arm 29 adapted, upon rotation of the screw, to contact with a stop-pin 30 fixed in the saddle 3. Thus it will be seen that by loosening the 90 clamp-screw the collar 27 and the arm 29 may be adjusted about the axis of the screw to any desired position and again locked to the screw 19. A predetermined rotation of the screw will then bring the arm into contact with the stop pin 30 which indicates to the operator that the work has been reduced to a predetermined size and should be removed from the machine.

To overcome slight inaccuracies in manufacture and to insure that the work-supporting surfaces 15 will initially contact with the work properly, the carriage 11 is pivotally supported on eccentric pins 22 and 23 formed integral with the shank 24 of the pivot 10 held in the arm 9 of the saddle. A knurled wheel 25, secured to the pin 22, affords means for rotating the pivot pin 10 and a knurled nut 26 threaded upon the pin 23 affords means for locking it in adjusted position. By loosening the nut 26 and rotating the pivot pin in the carriage 11 and the work-supporting block may be shifted bodily until the surfaces 15 properly contact with the work and in this position they may be held by again tightening the lock nut 26.

Without further analysis, the foregoing will so fully reveal the gist of this invention that others can, by applying current knowledge, readily adapt it for various utilizations by retaining one or more of the fea- 120 125 130

tures that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, we claim as new and desire to secure the following combinations and elements, or equivalents thereof, by Letters Patent of the United States:

1. A grinding machine combining a table, a grinding wheel; a saddle supported by said table; a member pivoted to said saddle; a work-supporting block carried by said member and adapted to engage the work at the side opposite said grinding wheel; and a single means for adjusting said member about its pivot to move it upwardly and outwardly so as to maintain said work-supporting block in contact with the work during a grinding operation.

2. A grinding machine combining a table; a grinding wheel; a standard carried by said table; a saddle adjustably mounted upon said standard; a member pivoted to said saddle at a point substantially above the axis of the grinding wheel; a work-supporting block secured to said member and adapted to engage the work at one side of and below the axis thereof; and a single means having a micrometer adjustment for swinging said member about its pivot to move said work-supporting block upwardly and towards the wheel for maintaining it in contact with the work during a grinding operation.

3. A work-support for grinding machines combining a saddle; a support for said saddle; means for securing said saddle to its support; a carriage pivoted to said saddle at a point substantially above the axis of the grinding wheel; a work-supporting block carried by said carriage and having converging work-engaging surfaces; and means for swinging said carriage about its pivot to move the work-engaging surfaces of the work-supporting block upwardly and outwardly for maintaining it in contact with the work during a grinding operation, said last named means comprising a lug carried by said carriage, a screw threaded through a portion of said saddle and having an end engaging said lug, and means for effecting manual rotation of said screw.

4. A work-supporting for grinding machines combining a saddle; in inclined support for said saddle; clamping means for adjustably securing said saddle to its sup-

port; an upwardly extending arm on said saddle; a carriage pivoted to said arm at one side of and above the axis of the work; a work-supporting block secured to said carriage and having inclined work-engaging surfaces; and a single manually actuated means carried by said saddle and acting upon said carriage to move the carriage and thereby the work-supporting block upwardly and outwardly about the pivot of 70 said carriage and toward the work to keep said surfaces in contact with the work during a grinding operation.

5. A work-support for grinding machines combining a table; an inclined standard 75 carried by said table and terminating at the top in a guide; a saddle fitted to said guide and having its lower end seated upon the inclined upper surface of said standard; an upwardly extending arm on said saddle; a member pivoted to said arm and provided with side walls depending at opposite sides of said saddle; a work-supporting block removably secured to said member and provided with inclined work-engaging surfaces, and adjusting screw threaded in said saddle and having an end contacting with said member between its depending walls and means for effecting manual adjustment of said screw to move said member and the 90 work-supporting block to maintain the work-engaging walls thereof in contact with the work during a grinding operation.

6. A work-support for grinding machines combining a saddle; a support for said saddle; a member pivoted to said saddle; a work-supporting block carried by said member; means for swinging said member about its pivot to move it upwardly and outwardly so as to keep the work-supporting block in 100 contact with the work during a grinding operation; and means for shifting the pivotal point of said member bodily on said saddle to effect an initial setting of said block with respect to the work.

7. A work support for grinding machines combining a saddle having an arm; a support for said saddle; a pivot-pin journaled in said arm and provided with eccentric portions; a member pivoted upon said 110 eccentric portions; a work supporting block carried by said member; means for manually rotating said pin to cause its eccentric portions to shift said member bodily; and means for locking said pin in its adjusted 115 position.

In witness whereof, we have hereunto subscribed our names.

SOL EINSTEIN.
HERMAN R. ISLER.
